No. 873,077.

PATENTED DEC. 10, 1907.

F. J. PATNOD.
COMB CEMENTING CLAMP.
APPLICATION FILED JAN. 2, 1907.

UNITED STATES PATENT OFFICE.

FELIX J. PATNOD, OF WORCESTER, MASSACHUSETTS, ASSIGNOR OF ONE-HALF TO JAMES FITZGERALD, OF WORCESTER, MASSACHUSETTS.

COMB-CEMENTING CLAMP.

No. 873,077.

Specification of Letters Patent.

Patented Dec. 10, 1907.

Application filed January 2, 1907. Serial No. 350,663.

To all whom it may concern:

Be it known that I, FELIX J. PATNOD, a citizen of the United States, residing at Worcester, in the county of Worcester, State of Massachusetts, have invented a certain new and useful Improvement in Comb-Cementing Clamps, of which the following is a specification, reference being had therein to the accompanying drawings.

10 Figure 1 is a side view of my invention showing lever and upper and lower clamps, which will be described hereafter. Fig. 2 is a top view of the same showing the spring by which the upper clamp is controlled. Fig. 3 is an end view of the same showing the ribs, which are constructed to strengthen the clamps. Figs. 4 and 5 show, respectively, an end and side view of one of the links which I shall describe hereinafter. Figs. 6 and 7 are front and side views, respectively, of the yoke. Figs. 8 and 9 are top and side views, respectively, of the guide block.

15 In Fig. 1, 1 is the lower clamp; 2, the upper clamp; 3, the hinge joining the upper and lower clamps; 4, the upper jaw; 5, the lower jaw; 6, the yoke; 7, the guide block; 8, the link; 9, the lever handle; 10, the lock-nut; 11, the shoulder on the upper clamp to prevent the lever going back too far; 12, the rubber face on the upper jaw; 13, the pin upon the guide block, 8, which is one of the axes of the link 7; 14, the other pin or axis of the same link set upon the upper jaw; 15, the pin upon which the yoke operates.

20 In Fig. 2, 16 is the spring which controls the upper jaw; 17 and 18 are the strengthening ribs of the upper jaw and of the corresponding positions in the lower jaw.

25 In Fig. 3, 19 shows the end of the lever handle pressing against the guide block, 8, the object of which will be more fully described hereafter.

30 In Fig. 5 may be seen the holes, 20 and 21, within which the pins, 13 and 14, operate and the recess, 22, to clear the guide block.

35 In Figs. 6 and 7 is shown the threaded hole 23 within which the lever handle 9, as shown in Fig. 1, is screwed. 24, 24' are the holes through which the axis pin 15 of the yoke passes.

Fig. 8 is an enlarged view of 8 as previously shown in Figs. 1 and 3 and here is shown the pin 13, described in connection with the link.

Fig. 9, 25 is the point where the end of the handle 9, shown in Fig. 3 and designated as 19, presses against the guide block.

I shall now describe the parts already designated in Figs. 1 to 9 inclusive in detail.

In Figs. 1 and 2, 1 is the lower clamp, 60 which is a flat sheet of metal, T shaped in form with the cross of the T forming the lower jaw of the clamp; 2 is also a T shaped plate, but shorter than 1 and hinged to it by the pin hinge 3. This pin hinge 3 is of the 65 ordinary form only broad enough so that the spring, which I shall describe later, may be placed upon it, the form of this hinge being best shown in Fig. 2. Upon the upper clamp 2 is the jaw 4, which is the cross portion of the T, already described, and fits with the other jaw 5, which is placed upon the lower and similar to it. Upon the lower clamp is fastened the yoke 6 by means of a pin which I shall describe hereafter and this 70 may be clearly seen in detail in Figs. 6 and 7. 75

7 is the guide block shown in Figs. 8 and 9 and this is slid up between the side plates of the yoke 6 with the point 25, which I shall describe later, at the top.

8 is the link which is fastened to a pin, to be described hereafter, on the upper clamp and also by the pin to the guide block 7. This link consists of two parts, each being similar to that shown in Figs. 4 and 5, one 85 being placed on each end of the pin 13, as shown in Fig. 8, forming a link such as is found in the ordinary bicycle chain, but in two parts.

9 is the handle of the lever composed of 90 the handle and yoke and the said handle is screwed into the threaded hole at the top of the yoke, to be described hereafter. Upon the screwed thread of this handle, I have placed a lock-nut, 10, to prevent the said handle from unscrewing. Upon the upper clamp is cast a shoulder 11 to prevent the lever from going back too far, as I shall describe in the operation.

12 is the rubber facing of the jaw 2 and 100 extends over the whole face thereof as may be seen in Figs. 1 and 3 and its object is to give to the jaw an elastic surface so as better to compress the comb when it is inserted therein for cementing; 13, the pin in the 105 guide block to which the link is fastened and it may be seen to the best advantage in Figs. 8 and 9; 14, the pin set in the rib of the

upper clamp to which the other end of the link is fastened and 15 is the pin set in the lower clamp upon which the yoke operates. These pins should be so placed that they should be in nearly a vertical line when the lever is in the position shown in Fig. 1.

16 is the spring to control the upper clamp and is the ordinary form of coil spring. One end of this spring is against the upper clamp 10 and the other end against the lower, thus giving to the jaws the tendency to spread apart; 17 and 18, the main and cross ribs of the upper or lower jaw, being the same in both, and are for the purpose of strengthening 15 the said jaws; 19, the end of the handle 9, as shown in Fig. 3, and it is this end that acts as an operating or regulating point of the handle 9, which I shall describe more fully hereafter; 20 and 21, the holes through 20 which the pins 13 and 14 act and their size must depend upon that of the said pins as they should fit within these holes.

The object of cutting the recess 22 in the link 8, already described, is that it may clear 25 the guide block when the lever is pushed forward, giving to the link the motion, which I shall describe more fully hereafter. 23 is the hole in the end of the yoke 6 through which the handle 9 is screwed, as 30 has already been stated. 24 and 24' are the holes in the said yoke through which the pin 15 passes.

The method of operation of the invention 35 is as follows. The comb to be cemented is placed between the jaws 4 and 5, the lever having been brought forward in the direction of the arrow A, and then the lever is shoved back until it strikes the shoulder 11. The motion of the lever in the direction of the 40 arrow A, already mentioned, causes the upper jaw to be raised and the turning of the same to its place, closes the jaws together. This is accomplished by means of the link 8, already described. The lower pin 14 is a 45 little out of the straight line, connecting the center 15 and the center 13 in the direction of the front of the clamp, in order that the lever may be locked when against the shoulder 11. This link in connection with the 50 yoke with axis at 15 makes a typical toggle-joint so that, as one of the points is moved to the side, the others must be brought nearer together. As the lever is pushed from its forward position into the position 55 shown in the figure, the three points 13, 14 and 15 come into line just before the guide block 7 strikes the shoulder 11 and then the points 13 and 15 pass the point 14 in the alinement, thus the lock previously described.

As the size of the combs to be cemented varies very materially, it is necessary to make the clamp adjustable and to adopt a method of adjusting which will keep the 65 jaws exactly parallel. To accomplish this,

I have placed upon the machine a lever which acts not only as a means for operating the jaws, but as a regulator. The method of doing this is as follows. To tighten the jaws, unscrew the lock-nut 10 upon the handle 9 and then screw down the handle 9 in the hole 23, as shown in Figs. 6 and 7, thus pressing down on the guide block 7 and also the link 8, which is connected with the said guide block and which in turn shoves down 75 on the upper jaw 2. To raise the jaw, the converse of this action is pursued. The guide block will always follow the handle 9, as it is raised, on account of the spring 16, shown in Fig. 2, which gives to the upper 80 jaw a tendency to open, thus shoving up on the link and the link upon the guide block.

When the handle has been regulated so that the jaws come the proper distance apart, the lock-nut 10 should be screwed 85 down against the top of the yoke 6, thus preventing the handle 9 from getting out of adjustment while the machine is in use. We see, therefore, that the link not only acts as a means of transmitting the desired motion, 90 but as a lock for the lever and the jaws.

The rubber face 12 in the upper jaw is placed upon the same, not only to firmly grip the comb when it is placed therein, but to compensate for any error that there may 95 be in the jaws not being parallel surfaces, due to the need of having a fixed hinge and having frequently to alter the position of the jaws from their normal position as shown in Fig. 1.

In the older forms of comb cementing clamps now in use, instead of our single bolt, which acts as a regulator, there are a series of ordinary bolts passed through the two plates at some distance apart and it is not only very 105 difficult but almost impossible to regulate all these bolts so that the pressure at one end of the comb is the same as at the other. In my invention, the regulating bolt comes in the middle so that the pressure cannot help but 110 be the same at both ends, which is a very material advantage. A slight difference in the level of either side of the jaw is not material, but it is very material that the ends should be exactly even and therefore exert an 115 even pressure.

My reason for cutting out the recess 22 is that the link may advance further, as the lever is brought forward, without striking against the edge 26 of the guide block 7. 120

One of the advantages of the link motion, which I have applied to my invention, is that when the jaws are apart and therefore previous to their coming in contact with the comb, when the lever is moved forward, 125 they approach each other very rapidly, but as the lever approaches the position as shown in Fig. 1 and the toggle-joint approaches the straight line, the motion becomes less rapid and therefore easier to operate, it being on 130

the same principle as a small gear running a larger one, and a great pressure can be obtained with little application of force.

I claim as my invention

- 5 1. In comb cementing clamps, the combination of a fixed jaw, a movable jaw pivotally mounted thereon, a lever pivoted on said fixed jaw and attached to said movable jaw by a toggle-joint to operate said movable jaw with relation to said fixed jaw and means upon said lever to adjust the relative position of said jaws, substantially as described.
- 10 2. In comb cementing clamps, the combination of a fixed jaw, a movable jaw pivotally mounted thereon, a lever pivoted on said fixed jaw and attached to said movable

jaw by a toggle-joint and an adjusting screw upon said lever to regulate the relative position of said jaws, substantially as described. 20

3. In comb cementing clamps, the combination of a fixed jaw, a movable jaw pivotally mounted thereon, a lever pivoted on said fixed jaw and attached to said movable jaw by a toggle-joint, to operate said movable jaw with relation to said fixed jaw and an adjustable handle upon said lever to regulate the relative position of said jaws. 25

In testimony whereof I affix my signature in presence of two witnesses.

FELIX J. PATNOD.
